UNITED STATES PATENT OFFICE

DELLA KNABENSHUE, OF GRAFTON, WEST VIRGINIA

ELECTRIC WIRE STRETCHER

Application filed July 6, 1931. Serial No. 549,057.

The primary object of this, my present invention, is the provision of a truck carried telephone wire stretcher, in which a mast made up of telescopically associated sections is caused to raise or lower by pressure of air compressed in the tank by the motor of the truck for raising the sections of the mast, there being valve controlled means for lowering the sections, the outer section carrying a pulley wheel over which is directed the wires that are arranged on rolls carried by the truck, together with means for steadyng the mast in its raised position, means for tilting the mast and for holding the same at desired inclinations and means carried by the mast for joining crossed wires.

A further object is the provision of a device for this purpose that may successfully be employed as a derrick.

The invention will be fully and comprehensively understood from a consideration of the following detailed description when read in connection with the accompanying drawings which form part of the application, with the understanding, however, that the improvement is capable of extended application and is not confined to the exact showing of the drawings nor to the precise construction described and, therefore, such changes and modifications may be made therefrom as do not affect the spirit of the invention nor exceed the scope thereof as expressed in the appended claim.

In the drawings:

Figure 1 is a side elevation of the improvement.

Figure 2 is a sectional view approximately on an enlarged scale on the line 2—2 of Figure 1.

Figure 3 is an elevation of the lower portion of the mast looking at a right angle to the showing in Figure 1.

Figure 4 is an enlarged sectional view approximately on the line 4—4 of Figure 3, with the outer mast section fully extended.

Figure 5 is a horizontal sectional view approximately on the line 5—5 of Figure 4.

Figure 6 is a sectional view approximately on the line 6—6 of Figure 1.

Figure 7 is a sectional view through the

valve that controls the air passage to the tilting means for the mast.

The truck 1 is mounted on suitable wheels 2 and is propelled by the usual motor (not shown). The motor is also employed for compressing and storing air in a tank 3.

At the forward end of the truck body there is secured to the bottom thereof plates 4, in the nature of discs which have upstanding brackets 5 having bearing openings for trunnions 6 on the lower and closed tubular section 7 of the mast. The lower plate 4 is fixed on the truck, but the upper plate, indicated for distinction by the numeral 8, (which carries the bracket 5) is pivotally secured thereto, as indicated by the numeral 9. The lower and closed end of the mast section 7 has a central opening therethrough surrounded by a nipple to which is connected and secured one end of a pipe 10 that leads from the tank 3. The passage through the pipe 10 is controlled by a hand operated valve 11 and the body of the valve is provided on one of its sides with a port 12. When the valve is turned to one position the air from the storage tank 3 will be directed into the mast section 7 and when the valve is turned to a second position the passage through the pipe to the air tank is cut off and air from the mast section is allowed to escape through the port 12.

In the showing of the drawings I have illustrated three mast sections which are telescopically associated but obviously any desired number of sections may be employed. All of the sections are tubular. The intermediate section is indicated by the numeral 13 and passes through the guide collar 14 which is screwed in the outer end of the mast section 7. The inner end of the mast section 13 is open but has secured therearound the collar that carries a cup-shaped washer 15 which frictionally engages with the bore of the mast section 7. The outer mast section 16 has its inner end headed, as at 17. This headed end which is received in the mast section 13 is closed and the mast section 16 is guided through a collar 18 on the upper end of the section 13. The mast section 16 has fixed upon its outer end a forked member 19 between whose arms there is journaled a grooved

roller 20, and this roller has trained there-over one of the telephone wires 21 which is wound around a drum 22 whose trunnions find bearings in openings in the sides of the truck body. Any desired number of wire carrying drums may be carried by the truck.

Secured to the outer end of the mast section 16 there is a guy or stabilizing cable 23. This cable is trained under a grooved wheel 24 whose trunnions are mounted in the bifurcated end of a bearing member 25 which is pivotally secured to an upright support 26 carried by the truck body. The cable 23 is directed from the sheave wheel 24 over another sheave wheel 25' whose trunnions are journaled in a suitable bracket 26' secured to the top of the mast section 7. The cable 23 is from thence directed into the mast section 7 and is secured to the mast section 13 adjacent to the lower and plunger end thereof. Pivotally secured, as at 27, to one side of the truck body 1 there is one of the closed ends of a cylinder 28. The cylinder has arranged therein a piston head 29 provided with a piston rod 30 which passes through a packing in the second closed end of the cylinder and which is pivotally secured to a bracket 31 on one side of the mast section 7. Angularly disposed tubes 32, respectively leading from a valve casing 33, are directed and communicate with the ends of the cylinder 28. The valve casing 33 is centrally provided with an outlet port 34 and has a pipe connection 35 with a substantially U-shaped pipe 36 whose ends communicate with both the bottom and one side of the mast section 7. The valve 37 in the casing 33 is of substantially rectangular formation as disclosed by Figure 7 but whose ends are rounded and the valve may be turned to direct air through either of the tubes 32 into either end of the cylinder 28, permitting the air from the second end of the cylinder to find an outlet through the port 34. The valve 37 is hand operated and the air directed therefrom will influence the piston 29 to cause its rod 30 to swing the mast on the trunnions 6 to desired angles.

In places where the country is clear and there are not many wires crossing the road the wire from the drum 22 is strung over the pulley or sheave wheel 20, as disclosed by Figure 1 of the drawings. The mast is lengthened on the truck until the top thereof is arranged above the telephone poles. As the truck moves along the mast is inclined, in a manner as just described, to cause the same to be arranged at either the right or the left of the telephone pole so that the wire drops onto the top of the pole. The guy or stabilizing cable steadies the mast when the sections thereof are moved outwardly from each other.

When there are wires crossing the road and a wire carried by the truck is to be strung above these wires the truck is stopped to hold the drum at a desired point, but if desired,

the drum may be arranged on a cart or the like which is fitted with bearings therefor. The wire 21 is hooked to a ring 37 on the end of a rod 38. The rod 38 has its sides provided with teeth 39, and these teeth are engaged by concaved and toothed jaws 40 carried on the outer ends of arched arms 41 which are pivotally connected to the ends of a substantially rectangular frame 42 that is horizontally supported on the outer end of the fork 19. The arms 41 are influenced toward each other through the medium of springs 43 and there are removable between the arms 41 spreader bars 44 that have depending arms 45. The arms are connected to cables 46, respectively, and these cables are wound around and secured to tubular members or drums 47 whose ends are journaled to the outstanding arms of substantially U-shaped brackets 48 which are fixed to the opposite sides of the mast section 7. The drums have turning wheels 49 on their outer ends, and in the hollow drums there are springs 50 connected thereto in the same manner as are the springs of a window shade roller and whereby the cables 46 are always under tension. When a wire across the road is reached the set of jaws adjacent thereto are released to provide a passage for the wire and the jaws are then returned to grip the rod. The second set of jaws are released while the wire passes therethrough and thereafter again grip the rod. The wire from the drum is thus being strung above the wire that crosses the road. This operation is repeated until the wire from the drum is strung to all of the crossing wires. By providing the truck with car wheels the apparatus can be used on a railway track and also the improvement may be employed as a derrick by merely disconnecting the piston rod 30 from the bracket 31 and by connecting telescopic stay rods between the top of the mast and eye or bracket members 51 fixed on the sides of the truck as disclosed by Figure 1 of the drawings. In this instance the base 8 of the mast is swung to a position rightangularly with respect to that disclosed by Figure 1 of the drawings so that the mast may be swung either forwardly or rearwardly on the trunnions 6.

It is believed that the foregoing description when read in connection with the drawings will fully and clearly set forth the simplicity of the construction and the advantages thereof to those skilled in the art to which the invention relates so that further detailed description will not be required. Obviously I do not wish to be restricted to the precise details herein set forth and, therefore, hold myself entitled to make such changes therefrom as fairly fall within the scope of what I claim.

Having described the invention, I claim:

In a device for the purpose set forth, a motor driven truck, a tank thereon contain-

ing air under pressure therein, a mast which is pivotally and revolvably supported on the truck and which includes a lower section, an intermediate section and an outer section, all of which are tubular and being telescopically received one in the other, means for introducing air from the tank into the lower mast section for expanding the mast, means for exhausting such air to permit of the telescoping of the mast sections, a wire directing sheave on the outer mast, a frame supported above the sheave, oppositely disposed arched jaw carrying rods pivoted to the frame, a toothed rod engaged by the jaws, and having a ring end for a wire, spring means influencing the arms toward each other, a spreader member between the arms, flexible elements connected to the spreader member and hand operated spring influenced drums around which the flexible elements are trained and secured in bearings on the lower mast sections for the drums.

In testimony whereof I affix my signature.
